UNITED STATES PATENT OFFICE.

FELIX WOOD, OF CLAREMONT, NEW HAMPSHIRE.

LASTING-JACK SUPPORT.

SPECIFICATION forming part of Letters Patent No. 423,584, dated March 18, 1890.

Application filed July 23, 1889. Serial No. 318,405. (No model.)

To all whom it may concern:

Be it known that I, FELIX WOOD, a citizen of the United States, residing at Claremont, in the county of Sullivan and State of New Hampshire, have invented certain new and useful Improvements in Lasting-Jack Supports; and I do declare the following to be a full, clear, and exact description of the invention, such as will enable others skilled in the art to 5 which it appertains to make and use the same, reference being had to the accompanying drawings, and to the letters of reference marked thereon, which form a part of this specification.

15 The invention relates to lasting-jack supports employed in the manufacture of boots and shoes. It will first be described in connection with the drawings, and then pointed out in the claim.

20 Figure 1 of the drawings is a perspective view of the lasting-jack; Fig. 2, a detail view of the bench with its end piece containing the pins, and Fig. 3 a similar view of the former.

In the drawings, A represents the wooden 25 bench, and through this extends a bolt B, on which works the lever-nut C. The bolt also passes through a longitudinal piece D, which connects two angular movable keepers E E, whose ends pass through the guides a a on 30 the sides of the bench. Through these keepers E E and on the bench slides the wooden former F, which is bifurcated so as to strad-

dle the bolt B with its arms f f, and thereby be guided in its movements. In each of the arms f f is a hole which receives the pins g g, 35 projecting from the end plate g of the bench. In each of these arms is also formed a shoulder, against which one end of the spring abuts.

The former F is rabbeted at f' to receive the metallic plate L, and the springs are protected by the metallic box M, which also serves as a guide to the former. The latter is pushed down on the springs, so as to project a greater or less extent from the bench, according to the length of the boot or shoe, 45 and this is done by means of the frame D E, which is forced down by the screw-bolt and its nut.

N is an arm to support the jack, which is fastened to the top of the board F.

50 What I claim as new, and desire to protect by Letters Patent, is—

A lasting-jack device consisting of the wooden bench A, screw-bolt B, with its lever-nut C, the frame D E, bifurcated wooden former F, and end plate G, carrying the pins g g, with springs thereon, all substantially as shown and described.

In testimony whereof I affix my signature in presence of two witnesses.

FELIX WOOD.
